UNITED STATES PATENT OFFICE.

HERBERT ETHERIDGE, OF WIMBLEDON PARK, ENGLAND, ASSIGNOR TO THE BAR-LOCK
TYPEWRITER COMPANY LIMITED, OF LONDON, ENGLAND.

PLATEN-CARRIAGE OF TYPE-WRITERS.

1,127,216.

Specification of Letters Patent.

Patented Feb. 2, 1915.

Application filed May 23, 1914. Serial No. 310,371.

To all whom it may concern:

Be it known that I, HERBERT ETHERIDGE, a subject of the King of England, residing at Wimbledon Park, in the county of 5 Surrey, England, have invented certain new and useful Improvements in Platen-Carriages of Type-Writers, of which the following is a specification.

The present invention relates to improvements in detachable platen carriages of typewriters having detaching means of that type which comprises stops upon the machine frame, coöoperating parts on the carriage-holder which engage the said stops and 10 register the carriage-holder with the frame, and means to lock the carriage-holder when thus in register, these parts being so arranged that the carriage-holder is removed by sliding it parallel with the frame of the 15 adjacent machine frame.

This invention is applied to detachable carriage-holders of the type in which the runners for the platen carriage constitute the longitudinal members of the holder, and 20 are joined at their ends by short end pieces or plates.

The present invention comprises a type-writer having a platen carriage-holder of the type described, and stops on the frame 25 and the engaging parts of the carriage-holder so arranged that the carriage-holder can be brought into locking position by sliding it parallel with the plane of the adjacent machine frame, wherein recessed lugs 30 are provided on the carriage holder to receive the stops, and latches are provided to draw the carriage-holder hard against the stops. There may be provided springs 35 which normally hold the latches in their 40 engaging position.

According to a feature of the invention the latches act also to draw the carriage-holder firmly down upon the machine frame, this result being obtained in the illustrated 45 construction by means of beveled parts on the latches, although obviously the beveled parts might equally well be located upon the stops.

The various features of the invention will 50 now be described with reference to the accompanying drawings, but it is to be understood that this is by way of exemplification and not of limitation, since the construction and arrangement of parts might

be modified without departing from the 55 spirit of the invention.

In the drawings Figure 1 is a view looking in the direction of the arrow in Fig. 2, Fig. 2 is a side sectional elevation of so much of the platen carriage-holder and 60 machine frame as is necessary for the understanding of the present invention, and Fig. 3 is a perspective view of one of the latches.

Like reference characters indicate like 65 parts in all the figures.

The top plate A which constitutes part of the frame of the machine instead of being horizontal as is usually the case is in the present instance at an angle thereto, and 70 is supported from the back A' of the frame of the machine as shown in Fig. 2. The top plate has screwed into it at either end a stud A² having a head A³, the under side of which is beveled or curved, as shown in 75 Fig. 2. The base of the platen carriage-holder comprises two end plates B upon which are mounted two longitudinal guide-bars B' in which the platen carrier is mounted for longitudinal movement. As the connecting devices at each end of the carriage-holder are similar, it will be necessary to describe only one and this accordingly will be done.

The end plate B is provided with a lug B² 85 which has a recess B⁴ in it which the stud A² is adapted to fit closely so that the head A³ will overlie the lug B². The end plate B has pivoted to it by means of a pin C a latch C' which carries at its end a hook C² 90 the parts being so proportioned that when the carriage-holder is in proper position on the top plate of the machine the hook may be swung about its pivot to underlie the head A³ of the stud. To provide for ease in operation the end plate B is recessed at B⁴ to take a coiled spring on one end of which is fitted into a hole in the bottom of the recess, the other end lying in another hole in the latch C', the arrangement being such that 100 the spring normally tends to force the latch in a direction to underlie the head A³. A pin B⁵ limits the movement in this direction. To move the latch in the reverse direction, it has an arm C³ projecting from it which 105 carries at its outer end a finger piece C⁴, so that the operator by pressing the finger piece may remove the hook from under the

head of the stud and so permit the carriage-holder to be slid away from the stud A².

In order that the entrance of the points of the hook under the head of the stud may be facilitated, these points are beveled at C⁵. It is to be noted that as the hook moves farther and farther under the head A³ it will, by reason of the beveled or curved under side of the head, force the carriage-holder down into close contact with the top plate of the machine, thus providing a rigid attachment.

In detaching the carriage-holder from the top plate of the machine the two finger pieces C⁴ are pressed inwardly so that the hooks C² are forced from underneath the heads A³ of the studs A². The platen carriage-holder is then slid along the top plate A in the direction of the arrow in Fig. 1, and is thereafter lifted bodily away from the top plate. This preliminary movement in the direction of the arrow in Fig. 1 clears the carriage-holder from the ribbon mechanism so that the tendency of the carriage-holder in the hands of a careless operator to contact with and damage the ribbon mechanism is considerably lessened.

What I claim as my invention and desire to secure by Letters Patent is—

30 1. In a typewriter the combination of a frame, stops thereon, a detachable carriage-holder comprising runners connected by end plates having lugs which extend parallel with the frame near the stops and are recessed at an edge to receive the stops as the carriage-holder is moved into position, and latches pivoted on the carriage-holder near its ends, each having a wedging surface and each being movable to engage a stop by said surface and draw the carriage-holder toward said stop, substantially as set forth.

2. In a typewriter the combination of a frame, stops thereon, a detachable carriage-holder comprising runners connected by end plates having lugs which extend parallel with the frame near the stops and are recessed at an edge to receive the stops as the carriage-holder is moved into position,

latches pivoted on the carriage-holder near its ends, each having a wedging surface and each being movable to engage a stop by said surface and draw the carriage-holder toward said stop, and springs on said latches tending always to move them into their engaging positions, substantially as set forth. 55

3. In a typewriter the combination of a frame, stops thereon, a detachable carriage-holder comprising runners connected by end plates having lugs which extend parallel with the frame near the stops and are recessed at an edge to receive the stops as the carriage-holder is moved into position, latches pivoted on the carriage-holder near its ends, each having a wedging surface and each being movable to engage a stop by said surface and draw the carriage-holder toward said stop, additional wedging surfaces being provided operative between said latches and a part operatively connected to the frame to press the carriage-holder firmly down upon said frame, substantially as set forth. 60 65

4. In a typewriter the combination of a frame, stops on said frame projecting therefrom and having heads, a detachable carriage-holder comprising runners connected by end plates having lugs which extend parallel with the frame near the stops and are recessed at an edge to receive the stops as the carriage-holder is moved into position 70 and latches pivoted on the carriage-holder near its ends, each having two wedging surfaces, one engaging the side of a stop to draw the carriage-holder toward it and the other engaging the underside of the head 75 of the stop to force the carriage-holder firmly down upon said frame, substantially as set forth.

In testimony whereof I have signed my name to this specification in the presence of 90 two subscribing witnesses.

HERBERT ETHERIDGE.
